ABSTRACT: In a spray gun the supply of coating material to the nozzle means of the gun is controlled by a pressure fluid-actuated differential servo piston means dividing the cylinder thereof in a first cylinder chamber around the stem and a second cylinder chamber opposite to the first cylinder chamber. During both strokes of the servo piston means the first cylinder chamber is pressurized by pressure fluid. A maneuvering valve is provided for either supplying pressure fluid to the second chamber for producing one of the strokes of the servo piston means against the action of pressure fluid in the first chamber, or relieving the pressure fluid in the second chamber for releasing the other stroke of the servo piston means under the action of said pressure fluid in the first chamber. More particularly the servo piston means may be of tandem design for quick actuation.

SPRAY GUN WITH PRESSURE OPERATED VALVE

This invention relates to spray guns for coating materials and more particularly to spray guns having pressure fluid-actuated servo piston means in the housing of the gun for the control of the coating material valve therein. Such spray guns are normally used for airless spraying of coating material under high pressure and for remotely controlling automatic spraying equipment intended for similar or other spraying operations. Conventionally the servo piston means are moved by a spring during one of the strokes in the reciprocation thereof and by pressure fluid during the other stroke.

It is an object of the invention to provide in spray guns of the above type, a simplified servo piston means in which both strokes of the servo piston means are powered by pressure fluid without actuation of the servo piston means by springs. A further object of the invention is to provide in spray guns of the above type a servo piston means of a design more efficient in utilizing the pressure fluid power acting thereagainst for quick opening or closing of the coating material valve. A still further object is to provide in spray guns of the above type a servo piston means of tandem design without actuating springs.

For the above and other purposes there is according to the invention provided a spray gun comprising a housing, nozzle means on said housing, means for supplying coating material under pressure to said nozzle means, a coating material valve for controlling the flow of such material through said nozzle means, a source of pressure fluid, a cylinder in said housing, differential servo piston means connected to said coating material valve and having a stem portion thereon sealingly but slidably guided in said housing, said differential servo piston means being movable in said cylinder to perform alternately opening and closing strokes therein under the action of pressure fluid from said source for controlling said coating material valve, said differential servo piston means dividing said cylinder in a first cylinder chamber around said stem and a second cylinder chamber opposite to said first cylinder chamber, means for keeping said first cylinder chamber pressurized by pressure fluid from said source during the strokes of said servo piston means, a maneuvering valve, and means controlled by said maneuvering valve for either supplying pressure fluid from said source to said second chamber for producing one of the strokes of said servo piston means against the action of said pressure fluid in said first chamber, or relieving the pressure fluid in said second chamber for releasing the other stroke of said servo piston means under the action of said pressure fluid in said first chamber.

The above and other purposes of the invention will become obvious from the following description and from the accompanying drawings in which three embodiments of the invention are illustrated by way of example. It should be understood that these embodiments are only illustrative of the invention and that various further modifications thereof may be made within the scope of the claims.

In the drawings FIG. 1 shows a longitudinal section through a remotely controlled automatic spray gun according to one embodiment of the invention. As depicted in FIG. 1 pressure fluid is supplied to the spray gun via a diagrammatically illustrated maneuvering valve such as to keep the coating material valve of the spray gun closed. FIG. 2 shows the spray gun in FIG. 1 in another position with the maneuvering valve in relief position and the coating material valve open. FIG. 3 shows a longitudinal section through an automatic spray gun of modified embodiment with the coating material valve therein closed. FIG. 4 shows a longitudinal section corresponding to FIG. 3 but with the coating material valve open. FIG. 5 shows a longitudinal section through a spray gun according to a third embodiment of the invention.

In FIGS. 1 and 2 the housing of the spray gun is designated by 10 and is provided with a servo piston means consisting of a differential piston 13 controlling the flow of paint from a first, or paint cylinder chamber 20. The piston 13 has a stem portion 13¹ thereon sealingly but slidably guided in the housing 10

5 in a bore 29 in free communication with the atmosphere. The piston 13 is journaled for reciprocation in a cylinder 14¹ provided in a backhead 14 which is screwed to the rear end of the spray gun housing 10. The differential piston 13 consists of a resilient packing cup 15 slidably cooperating with the cylinder 14¹ and a washer 30 retaining the packing cup 15 against a rear shoulder on the stem 13¹. The washer 30 is locked by a tightening nut screwed onto the stem 13. The packing cup 15 divides the cylinder 14¹ in two second and third cylinder chambers 16, 12 of which said chamber 16 is disposed around the stem 13¹ and said third chamber 12 is at the end thereof opposite to chamber 16. By means of a conduit 17 the second cylinder chamber 12 is connectable via a maneuvering valve 11 alternatively to a supply hose and a source 37 of pressure fluid such as compressed air or to the atmosphere.

10 By means of a stop screw there is affixed to the stem 13¹ of differential piston 13 the stem 18 of a coating material valve 19. The valve 19 is disposed in a coating material or paint chamber 20 in the front portion of the housing 10. At the traverse into the paint chamber 20 the coating material valve stem 18 is surrounded by a sealing ring 28 of packing material which is compressed by the aid of a packing nut 27. Via a conduit 21 the paint chamber 20 is supplied with coating material under high pressure of the order of magnitude of 300 atmospheres. The paint chamber 20 has an outlet orifice 31 controlled by the valve 19. An atomizing nozzle means 25 is kept in place coaxially with and in front of the outlet orifice 31 by means of a retaining nut 22.

15 The housing 10 is provided with a cross bore 26 disposed proximate to the coating material valve axis and serving as a suspending or fixation hole for the housing 10 when the spray gun is to be mounted for automated work.

20 In FIG. 1 the maneuvering valve 11 is set to a position in which pressure fluid is supplied from the source 37 via the maneuvering valve 11 and conduit 17 to the cylinder chamber 12. The differential piston 13 is thus power biased in forward direction towards the outlet orifice 31 and the paint valve 19 is maintained firmly on its seat around the outlet orifice 31. The 25 edge of the packing cup 15 is turned towards the cylinder chamber 16 and in the position depicted in FIG. 1 the cup 15 consequently acts as a check valve means allowing pressure fluid to flow to the cylinder chamber 16 while the cylinder chamber 12 is pressurized. When the maneuvering valve 11 is 30 switched to exhaust cylinder chamber 12, FIG. 2, the charge of pressure fluid trapped in cylinder chamber 16 expands, acts against piston packing cup 15 and displaces the differential piston 13 rearwardly away from the outlet orifice 31. The 35 opening stroke of the coating material valve 19 thus started is amplified by coating material pressure in the paint chamber 20 which acts on the valve 19 and valve stem 18 axially in the 40 opening direction thereof.

45 As soon as the maneuvering valve 11 is returned to the position indicated in FIG. 1, the cylinder chamber 12 is again filled by pressure fluid and the differential piston 13 is moved in its closing stroke forwardly overcoming the counter pressure in cylinder chamber 16. Cylinder chamber 16 is charged at the initial stage simultaneously with chamber 12 by pressure fluid entering chamber 12 and flowing past the packing cup 15. 50 During the closing stroke the differential piston 13 closes the coating material valve 19 and compresses simultaneously therewith the pressure fluid charge in cylinder chamber 16 to a pressure slightly higher than line pressure.

55 In the embodiment depicted in FIGS. 3 and 4 the servo piston means which at the stem end thereof is affixed to the coating material valve stem 18, is of tandem design. In the spray gun housing 32 the servo piston means is thus provided with an outer tandem piston head 13 affixed to a stem 13¹ and 60 sealingly but slidably guided in a partition 34 within the housing 32. Similar to the embodiment in FIGS. 1, 2 piston head 13 and stem 13¹ provide a differential piston guided in a bore 14¹ in a backhead 14. In the housing 32 there is provided coaxially with the bore 14 a bore 33 in which is slidably an intermediate 65 pistonhead 36 incorporating a packing cup 35. The intermediate pistonhead 36 is provided with a bore 37 in which is slidably a piston 38. The piston 38 is provided with a bore 39 in which is slidably a piston 40. The piston 40 is provided with a bore 41 in which is slidably a piston 42. The piston 42 is provided with a bore 43 in which is slidably a piston 44. The piston 44 is provided with a bore 45 in which is slidably a piston 46. The piston 46 is provided with a bore 47 in which is slidably a piston 48. The piston 48 is provided with a bore 49 in which is slidably a piston 50. The piston 50 is provided with a bore 51 in which is slidably a piston 52. The piston 52 is provided with a bore 53 in which is slidably a piston 54. The piston 54 is provided with a bore 55 in which is slidably a piston 56. The piston 56 is provided with a bore 57 in which is slidably a piston 58. The piston 58 is provided with a bore 59 in which is slidably a piston 60. The piston 60 is provided with a bore 61 in which is slidably a piston 62. The piston 62 is provided with a bore 63 in which is slidably a piston 64. The piston 64 is provided with a bore 65 in which is slidably a piston 66. The piston 66 is provided with a bore 67 in which is slidably a piston 68. The piston 68 is provided with a bore 69 in which is slidably a piston 70. The piston 70 is provided with a bore 71 in which is slidably a piston 72. The piston 72 is provided with a bore 73 in which is slidably a piston 74. The piston 74 is provided with a bore 75 in which is slidably a piston 76. The piston 76 is provided with a bore 77 in which is slidably a piston 78. The piston 78 is provided with a bore 79 in which is slidably a piston 80. The piston 80 is provided with a bore 81 in which is slidably a piston 82. The piston 82 is provided with a bore 83 in which is slidably a piston 84. The piston 84 is provided with a bore 85 in which is slidably a piston 86. The piston 86 is provided with a bore 87 in which is slidably a piston 88. The piston 88 is provided with a bore 89 in which is slidably a piston 90. The piston 90 is provided with a bore 91 in which is slidably a piston 92. The piston 92 is provided with a bore 93 in which is slidably a piston 94. The piston 94 is provided with a bore 95 in which is slidably a piston 96. The piston 96 is provided with a bore 97 in which is slidably a piston 98. The piston 98 is provided with a bore 99 in which is slidably a piston 100. The piston 100 is provided with a bore 101 in which is slidably a piston 102. The piston 102 is provided with a bore 103 in which is slidably a piston 104. The piston 104 is provided with a bore 105 in which is slidably a piston 106. The piston 106 is provided with a bore 107 in which is slidably a piston 108. The piston 108 is provided with a bore 109 in which is slidably a piston 110. The piston 110 is provided with a bore 111 in which is slidably a piston 112. The piston 112 is provided with a bore 113 in which is slidably a piston 114. The piston 114 is provided with a bore 115 in which is slidably a piston 116. The piston 116 is provided with a bore 117 in which is slidably a piston 118. The piston 118 is provided with a bore 119 in which is slidably a piston 120. The piston 120 is provided with a bore 121 in which is slidably a piston 122. The piston 122 is provided with a bore 123 in which is slidably a piston 124. The piston 124 is provided with a bore 125 in which is slidably a piston 126. The piston 126 is provided with a bore 127 in which is slidably a piston 128. The piston 128 is provided with a bore 129 in which is slidably a piston 130. The piston 130 is provided with a bore 131 in which is slidably a piston 132. The piston 132 is provided with a bore 133 in which is slidably a piston 134. The piston 134 is provided with a bore 135 in which is slidably a piston 136. The piston 136 is provided with a bore 137 in which is slidably a piston 138. The piston 138 is provided with a bore 139 in which is slidably a piston 140. The piston 140 is provided with a bore 141 in which is slidably a piston 142. The piston 142 is provided with a bore 143 in which is slidably a piston 144. The piston 144 is provided with a bore 145 in which is slidably a piston 146. The piston 146 is provided with a bore 147 in which is slidably a piston 148. The piston 148 is provided with a bore 149 in which is slidably a piston 150. The piston 150 is provided with a bore 151 in which is slidably a piston 152. The piston 152 is provided with a bore 153 in which is slidably a piston 154. The piston 154 is provided with a bore 155 in which is slidably a piston 156. The piston 156 is provided with a bore 157 in which is slidably a piston 158. The piston 158 is provided with a bore 159 in which is slidably a piston 160. The piston 160 is provided with a bore 161 in which is slidably a piston 162. The piston 162 is provided with a bore 163 in which is slidably a piston 164. The piston 164 is provided with a bore 165 in which is slidably a piston 166. The piston 166 is provided with a bore 167 in which is slidably a piston 168. The piston 168 is provided with a bore 169 in which is slidably a piston 170. The piston 170 is provided with a bore 171 in which is slidably a piston 172. The piston 172 is provided with a bore 173 in which is slidably a piston 174. The piston 174 is provided with a bore 175 in which is slidably a piston 176. The piston 176 is provided with a bore 177 in which is slidably a piston 178. The piston 178 is provided with a bore 179 in which is slidably a piston 180. The piston 180 is provided with a bore 181 in which is slidably a piston 182. The piston 182 is provided with a bore 183 in which is slidably a piston 184. The piston 184 is provided with a bore 185 in which is slidably a piston 186. The piston 186 is provided with a bore 187 in which is slidably a piston 188. The piston 188 is provided with a bore 189 in which is slidably a piston 190. The piston 190 is provided with a bore 191 in which is slidably a piston 192. The piston 192 is provided with a bore 193 in which is slidably a piston 194. The piston 194 is provided with a bore 195 in which is slidably a piston 196. The piston 196 is provided with a bore 197 in which is slidably a piston 198. The piston 198 is provided with a bore 199 in which is slidably a piston 200. The piston 200 is provided with a bore 201 in which is slidably a piston 202. The piston 202 is provided with a bore 203 in which is slidably a piston 204. The piston 204 is provided with a bore 205 in which is slidably a piston 206. The piston 206 is provided with a bore 207 in which is slidably a piston 208. The piston 208 is provided with a bore 209 in which is slidably a piston 210. The piston 210 is provided with a bore 211 in which is slidably a piston 212. The piston 212 is provided with a bore 213 in which is slidably a piston 214. The piston 214 is provided with a bore 215 in which is slidably a piston 216. The piston 216 is provided with a bore 217 in which is slidably a piston 218. The piston 218 is provided with a bore 219 in which is slidably a piston 220. The piston 220 is provided with a bore 221 in which is slidably a piston 222. The piston 222 is provided with a bore 223 in which is slidably a piston 224. The piston 224 is provided with a bore 225 in which is slidably a piston 226. The piston 226 is provided with a bore 227 in which is slidably a piston 228. The piston 228 is provided with a bore 229 in which is slidably a piston 230. The piston 230 is provided with a bore 231 in which is slidably a piston 232. The piston 232 is provided with a bore 233 in which is slidably a piston 234. The piston 234 is provided with a bore 235 in which is slidably a piston 236. The piston 236 is provided with a bore 237 in which is slidably a piston 238. The piston 238 is provided with a bore 239 in which is slidably a piston 240. The piston 240 is provided with a bore 241 in which is slidably a piston 242. The piston 242 is provided with a bore 243 in which is slidably a piston 244. The piston 244 is provided with a bore 245 in which is slidably a piston 246. The piston 246 is provided with a bore 247 in which is slidably a piston 248. The piston 248 is provided with a bore 249 in which is slidably a piston 250. The piston 250 is provided with a bore 251 in which is slidably a piston 252. The piston 252 is provided with a bore 253 in which is slidably a piston 254. The piston 254 is provided with a bore 255 in which is slidably a piston 256. The piston 256 is provided with a bore 257 in which is slidably a piston 258. The piston 258 is provided with a bore 259 in which is slidably a piston 260. The piston 260 is provided with a bore 261 in which is slidably a piston 262. The piston 262 is provided with a bore 263 in which is slidably a piston 264. The piston 264 is provided with a bore 265 in which is slidably a piston 266. The piston 266 is provided with a bore 267 in which is slidably a piston 268. The piston 268 is provided with a bore 269 in which is slidably a piston 270. The piston 270 is provided with a bore 271 in which is slidably a piston 272. The piston 272 is provided with a bore 273 in which is slidably a piston 274. The piston 274 is provided with a bore 275 in which is slidably a piston 276. The piston 276 is provided with a bore 277 in which is slidably a piston 278. The piston 278 is provided with a bore 279 in which is slidably a piston 280. The piston 280 is provided with a bore 281 in which is slidably a piston 282. The piston 282 is provided with a bore 283 in which is slidably a piston 284. The piston 284 is provided with a bore 285 in which is slidably a piston 286. The piston 286 is provided with a bore 287 in which is slidably a piston 288. The piston 288 is provided with a bore 289 in which is slidably a piston 290. The piston 290 is provided with a bore 291 in which is slidably a piston 292. The piston 292 is provided with a bore 293 in which is slidably a piston 294. The piston 294 is provided with a bore 295 in which is slidably a piston 296. The piston 296 is provided with a bore 297 in which is slidably a piston 298. The piston 298 is provided with a bore 299 in which is slidably a piston 300. The piston 300 is provided with a bore 301 in which is slidably a piston 302. The piston 302 is provided with a bore 303 in which is slidably a piston 304. The piston 304 is provided with a bore 305 in which is slidably a piston 306. The piston 306 is provided with a bore 307 in which is slidably a piston 308. The piston 308 is provided with a bore 309 in which is slidably a piston 310. The piston 310 is provided with a bore 311 in which is slidably a piston 312. The piston 312 is provided with a bore 313 in which is slidably a piston 314. The piston 314 is provided with a bore 315 in which is slidably a piston 316. The piston 316 is provided with a bore 317 in which is slidably a piston 318. The piston 318 is provided with a bore 319 in which is slidably a piston 320. The piston 320 is provided with a bore 321 in which is slidably a piston 322. The piston 322 is provided with a bore 323 in which is slidably a piston 324. The piston 324 is provided with a bore 325 in which is slidably a piston 326. The piston 326 is provided with a bore 327 in which is slidably a piston 328. The piston 328 is provided with a bore 329 in which is slidably a piston 330. The piston 330 is provided with a bore 331 in which is slidably a piston 332. The piston 332 is provided with a bore 333 in which is slidably a piston 334. The piston 334 is provided with a bore 335 in which is slidably a piston 336. The piston 336 is provided with a bore 337 in which is slidably a piston 338. The piston 338 is provided with a bore 339 in which is slidably a piston 340. The piston 340 is provided with a bore 341 in which is slidably a piston 342. The piston 342 is provided with a bore 343 in which is slidably a piston 344. The piston 344 is provided with a bore 345 in which is slidably a piston 346. The piston 346 is provided with a bore 347 in which is slidably a piston 348. The piston 348 is provided with a bore 349 in which is slidably a piston 350. The piston 350 is provided with a bore 351 in which is slidably a piston 352. The piston 352 is provided with a bore 353 in which is slidably a piston 354. The piston 354 is provided with a bore 355 in which is slidably a piston 356. The piston 356 is provided with a bore 357 in which is slidably a piston 358. The piston 358 is provided with a bore 359 in which is slidably a piston 360. The piston 360 is provided with a bore 361 in which is slidably a piston 362. The piston 362 is provided with a bore 363 in which is slidably a piston 364. The piston 364 is provided with a bore 365 in which is slidably a piston 366. The piston 366 is provided with a bore 367 in which is slidably a piston 368. The piston 368 is provided with a bore 369 in which is slidably a piston 370. The piston 370 is provided with a bore 371 in which is slidably a piston 372. The piston 372 is provided with a bore 373 in which is slidably a piston 374. The piston 374 is provided with a bore 375 in which is slidably a piston 376. The piston 376 is provided with a bore 377 in which is slidably a piston 378. The piston 378 is provided with a bore 379 in which is slidably a piston 380. The piston 380 is provided with a bore 381 in which is slidably a piston 382. The piston 382 is provided with a bore 383 in which is slidably a piston 384. The piston 384 is provided with a bore 385 in which is slidably a piston 386. The piston 386 is provided with a bore 387 in which is slidably a piston 388. The piston 388 is provided with a bore 389 in which is slidably a piston 390. The piston 390 is provided with a bore 391 in which is slidably a piston 392. The piston 392 is provided with a bore 393 in which is slidably a piston 394. The piston 394 is provided with a bore 395 in which is slidably a piston 396. The piston 396 is provided with a bore 397 in which is slidably a piston 398. The piston 398 is provided with a bore 399 in which is slidably a piston 400. The piston 400 is provided with a bore 401 in which is slidably a piston 402. The piston 402 is provided with a bore 403 in which is slidably a piston 404. The piston 404 is provided with a bore 405 in which is slidably a piston 406. The piston 406 is provided with a bore 407 in which is slidably a piston 408. The piston 408 is provided with a bore 409 in which is slidably a piston 410. The piston 410 is provided with a bore 411 in which is slidably a piston 412. The piston 412 is provided with a bore 413 in which is slidably a piston 414. The piston 414 is provided with a bore 415 in which is slidably a piston 416. The piston 416 is provided with a bore 417 in which is slidably a piston 418. The piston 418 is provided with a bore 419 in which is slidably a piston 420. The piston 420 is provided with a bore 421 in which is slidably a piston 422. The piston 422 is provided with a bore 423 in which is slidably a piston 424. The piston 424 is provided with a bore 425 in which is slidably a piston 426. The piston 426 is provided with a bore 427 in which is slidably a piston 428. The piston 428 is provided with a bore 429 in which is slidably a piston 430. The piston 430 is provided with a bore 431 in which is slidably a piston 432. The piston 432 is provided with a bore 433 in which is slidably a piston 434. The piston 434 is provided with a bore 435 in which is slidably a piston 436. The piston 436 is provided with a bore 437 in which is slidably a piston 438. The piston 438 is provided with a bore 439 in which is slidably a piston 440. The piston 440 is provided with a bore 441 in which is slidably a piston 442. The piston 442 is provided with a bore 443 in which is slidably a piston 444. The piston 444 is provided with a bore 445 in which is slidably a piston 446. The piston 446 is provided with a bore 447 in which is slidably a piston 448. The piston 448 is provided with a bore 449 in which is slidably a piston 450. The piston 450 is provided with a bore 451 in which is slidably a piston 452. The piston 452 is provided with a bore 453 in which is slidably a piston 454. The piston 454 is provided with a bore 455 in which is slidably a piston 456. The piston 456 is provided with a bore 457 in which is slidably a piston 458. The piston 458 is provided with a bore 459 in which is slidably a piston 460. The piston 460 is provided with a bore 461 in which is slidably a piston 462. The piston 462 is provided with a bore 463 in which is slidably a piston 464. The piston 464 is provided with a bore 465 in which is slidably a piston 466. The piston 466 is provided with a bore 467 in which is slidably a piston 468. The piston 468 is provided with a bore 469 in which is slidably a piston 470. The piston 470 is provided with a bore 471 in which is slidably a piston 472. The piston 472 is provided with a bore 473 in which is slidably a piston 474. The piston 474 is provided with a bore 475 in which is slidably a piston 476. The piston 476 is provided with a bore 477 in which is slidably a piston 478. The piston 478 is provided with a bore 479 in which is slidably a piston 480. The piston 480 is provided with a bore 481 in which is slidably a piston 482. The piston 482 is provided with a bore 483 in which is slidably a piston 484. The piston 484 is provided with a bore 485 in which is slidably a piston 486. The piston 486 is provided with a bore 487 in which is slidably a piston 488. The piston 488 is provided with a bore 489 in which is slidably a piston 490. The piston 490 is provided with a bore 491 in which is slidably a piston 492. The piston 492 is provided with a bore 493 in which is slidably a piston 494. The piston 494 is provided with a bore 495 in which is slidably a piston 496. The piston 496 is provided with a bore 497 in which is slidably a piston 498. The piston 498 is provided with a bore 499 in which is slidably a piston 500. The piston 500 is provided with a bore 501 in which is slidably a piston 502. The piston 502 is provided with a bore 503 in which is slidably a piston 504. The piston 504 is provided with a bore 505 in which is slidably a piston 506. The piston 506 is provided with a bore 507 in which is slidably a piston 508. The piston 508 is provided with a bore 509 in which is slidably a piston 510. The piston 510 is provided with a bore 511 in which is slidably a piston 512. The piston 512 is provided with a bore 513 in which is slidably a piston 514. The piston 514 is provided with a bore 515 in which is slidably a piston 516. The piston 516 is provided with a bore 517 in which is slidably a piston 518. The piston 518 is provided with a bore 519 in which is slidably a piston 520. The piston 520 is provided with a bore 521 in which is slidably a piston 522. The piston 522 is provided with a bore 523 in which is slidably a piston 524. The piston 524 is provided with a bore 525 in which is slidably a piston 526. The piston 526 is provided with a bore 527 in which is slidably a piston 528. The piston 528 is provided with a bore 529 in which is slidably a piston 530. The piston 530 is provided with a bore 531 in which is slidably a piston 532. The piston 532 is provided with a bore 533 in which is slidably a piston 534. The piston 534 is provided with a bore 535 in which is slidably a piston 536. The piston 536 is provided with a bore 537 in which is slidably a piston 538. The piston 538 is provided with a bore 539 in which is slidably a piston 540. The piston 540 is provided with a bore 541 in which is slidably a piston 542. The piston 542 is provided with a bore 543 in which is slidably a piston 544. The piston 544 is provided with a bore 545 in which is slidably a piston 546. The piston 546 is provided with a bore 547 in which is slidably a piston 548. The piston 548 is provided with a bore 549 in which is slidably a piston 550. The piston 550 is provided with a bore 551 in which is slidably a piston 552. The piston 552 is provided with a bore 553 in which is slidably a piston 554. The piston 554 is provided with a bore 555 in which is slidably a piston 556. The piston 556 is provided with a bore 557 in which is slidably a piston 558. The piston 558 is provided with a bore 559 in which is slidably a piston 560. The piston 560 is provided with a bore 561 in which is slidably a piston 562. The piston 562 is provided with a bore 563 in which is slidably a piston 564. The piston 564 is provided with a bore 565 in which is slidably a piston 566. The piston 566 is provided with a bore 567 in which is slidably a piston 568. The piston 568 is provided with a bore 569 in which is slidably a piston 570. The piston 570 is provided with a bore 571 in which is slidably a piston 572. The piston 572 is provided with a bore 573 in which is slidably a piston 574. The piston 574 is provided with a bore 575 in which is slidably a piston 576. The piston 576 is provided with a bore 577 in which is slidably a piston 578. The piston 578 is provided with a bore 579 in which is slidably a piston 580. The piston 580 is provided with a bore 581 in which is slidably a piston 582. The piston 582 is provided with a bore 583 in which is slidably a piston 584. The piston 584 is provided with a bore 585 in which is slidably a piston 586. The piston 586 is provided with a bore 587 in which is slidably a piston 588. The piston 588 is provided with a bore 589 in which is slidably a piston 590. The piston 590 is provided with a bore 591 in which is slidably a piston 592. The piston 592 is provided with a bore 593 in which is slidably a piston 594. The piston 594 is provided with a bore 595 in which is slidably a piston 596. The piston 596 is provided with a bore 597 in which is slidably a piston 598. The piston 598 is provided with a bore 599 in which is slidably a piston 600. The piston 600 is provided with a bore 601 in which is slidably a piston 602. The piston 602 is provided with a bore 603 in which is slidably a piston 604. The piston 604 is provided with a bore 605 in which is slidably a piston 606. The piston 606 is provided with a bore 607 in which is slidably a piston 608. The piston 608 is provided with a bore 609 in which is slidably a piston 610. The piston 610 is provided with a bore 611 in which is slidably a piston 612. The piston 612 is provided with a bore 613 in which is slidably a piston 614. The piston 614 is provided with a bore 615 in which is slidably a piston 616. The piston 616 is provided with a bore 617 in which is slidably a piston 618. The piston 618 is provided with a bore 619 in which is slidably a piston 620. The piston 620 is provided with a bore 621 in which is slidably a piston 622. The piston 622 is provided with a bore 623 in which is slidably a piston 624. The piston 624 is provided with a bore 625 in which is slidably a piston 626. The piston 626 is provided with a bore 627 in which is slidably a piston 628. The piston 628 is provided with a bore 629 in which is slidably a piston 630. The piston 630 is provided with a bore 631 in which is slidably a piston 632. The piston 632 is provided with a bore 633 in which is slidably a piston 634. The piston 634 is provided with a bore 635 in which is slidably a piston 636. The piston 636 is provided with a bore 637 in which is slidably a piston 638. The piston 638 is provided with a bore 639 in which is slidably a piston 640. The piston 640 is provided with a bore 641 in which is slidably a piston 642. The piston 642 is provided with a bore 643 in which is slidably a piston 644. The piston 644 is provided with a bore 645 in which is slidably a piston 646. The piston 646 is provided with a bore 647 in which is slidably a piston 648. The piston 648 is provided with a bore 649 in which is slidably a piston 650. The piston 650 is provided with a bore 651 in which is slidably a piston 652. The piston 652 is provided with a bore 653 in which is slidably a piston 654. The piston 654 is provided with a bore 655 in which is slidably a piston 656. The piston 656 is provided with a bore 657 in which is slidably a piston 658. The piston 658 is provided with a bore 659 in which is slidably a piston 660. The piston 660 is provided with a bore 661 in which is slidably a piston 662. The piston 662 is provided with a bore 663 in which is slidably a piston 664. The piston 664 is provided with a bore 665 in which is slidably a piston 666. The piston 666 is provided with a bore 667 in which is slidably a piston 668. The piston 668 is provided with a bore 669 in which is slidably a piston 670. The piston 670 is provided with a bore 671 in which is slidably a piston 672. The piston 672 is provided with a bore 673 in which is slidably a piston 674. The piston 674 is provided with a bore 675 in which is slidably a piston 676. The piston 676 is provided with a bore 677 in which is slidably a piston 678. The piston 678 is provided with a bore 679 in which is slidably a piston 680. The piston 680 is provided with a bore 681 in which is slidably a piston 682. The piston 682 is provided with a bore 683 in which is slidably a piston 684. The piston 684 is provided with a bore 685 in which is slidably a piston 686. The piston 686 is provided with a bore 687 in which is slidably a piston 688. The piston 688 is provided with a bore 689 in which is slidably a piston 690. The piston 690 is provided with a bore 691 in which is slidably a piston 692. The piston 692 is provided with a bore 693 in which is slidably a piston 694. The piston 694 is provided with a bore 695 in which is slidably a piston 696. The piston 696 is provided with a bore 697 in which is slidably a piston 698. The piston 698 is provided with a bore 699 in which is slidably a piston 700. The piston 700 is provided with a bore 701 in which is slidably a piston 702. The piston 702 is provided with a bore 7

mediate pistonhead 36 is affixed to the stem 13¹ of the pistonhead 13 and is kept in position thereagainst by an extension stem 13¹¹ which is screwed onto the forward end of stem 13¹. Between the intermediate pistonhead 36 and the partition 34 there is formed a third cylinder chamber 24 disposed in the bore 33. The second cylinder chamber 12 in the backhead 14 communicates via inner passages 23 provided in the stem 13¹ with the third cylinder chamber 24.

When pressure fluid is supplied from the source 37 via the maneuvering valve 11 to cylinder chamber 12 in the backhead 14, the packing cup 15 will as before act in check valve manner and cylinder chamber 16 between the outer pistonhead 13 and the partition 34 will thus be charged simultaneously with pressure fluid entering cylinder chamber 12. As a result the pistonhead 12 will be actuated by an axial force to perform the closing stroke of the tandem piston in the direction of the outlet orifice 31 of the coating material valve 19. This force is amplified by the cylinder chamber 24 between the packing cup 35 of pistonhead 36 and the partition 34 becoming pressurized simultaneously with chamber 12 via the passages 23, and the tandem piston will thus perform its closing stroke under pressure bias against both pistonheads 13, 36.

As soon as the maneuvering valve 11 is switched to exhaust position, FIG. 4, the cylinder chambers 24 and 12 will be exhausted. Pressure fluid trapped in cylinder chamber 16 behind the packing cup 15 will now be free to expand for performing the opening stroke of the tandem piston and for opening the coating material valve 19. The opening movement is amplified by coating material pressure starting to act in the paint chamber 20 on the coating material valve 19 in the opening direction thereof as soon as the valve 19 has left its seat around orifice 31. The tandem design of the servo piston means increases the total piston area available for the closing stroke and reduces the dimensions of the servo piston means allowing quick operation.

In the embodiment exemplified in FIG. 5 the servo piston means in the spray gun housing 38 is identical in operation with the embodiment depicted in FIGS. 3, 4. The backhead 14, however, is closed at the rear end thereof by means of a plug 39 and pressure fluid is supplied to the tandem piston for closing purposes from the source 37 directly to both cylinder chambers 24, 16. The supply of pressure fluid is controlled by a maneuvering valve 40 which is actuated by a trigger 41 and may be moved against the action of a spring 42 from a position a in which the source 37 is connected to both cylinder chambers 24, 16 to a position b in which cylinder chamber 16 is connected to the source 37 whilst the cylinder chamber 24 is exhausted via a conduit 43. Via the passages 23 cylinder chamber 12 is of course exhausted simultaneously with cylinder chamber 24. In connection with the depicted valve arrangement it is particularly suitable to arrange the maneuvering valve 40 in a pistol type grip 44, diagrammatically depicted by broken lines in FIG. 5, by which the spray gun housing 38 may be directed and used manually.

I claim:

1. A spray gun comprising a housing, nozzle means on said housing, means for supplying coating material under pressure to said nozzle means, a piston operating in said housing, a coating material valve mounted on an end of said piston within a first cylinder chamber for controlling the flow of such material through said nozzle means, a source of pressure fluid, an additional cylinder in said housing, a differential servo pistonhead connected to said piston at an end opposite to said coating material valve, said piston having an intermediate stem portion thereon sealing but slidably guided in said housing, said differential servo pistonhead being movable in said additional cylinder to perform alternately opening and closing

strokes therein under the action of pressure fluid from said source for controlling said coating material valve, said differential servo pistonhead dividing said additional cylinder in a second cylinder chamber around said stem and a third cylinder chamber adjacent to said second cylinder chamber, a passage connected between said second and third cylinder chambers, a one-way valve means arranged in said passage for controlling the flowing of pressure fluid only in the direction from said third cylinder chamber into said second cylinder chamber, means for flowing pressure fluid from said source into said third cylinder chamber and from thence through said one-way valve means into said second cylinder chamber, a maneuvering valve, and means controlled by said maneuvering valve for either supplying pressure fluid from said source to said third chamber for producing said closing stroke of said servo piston head against the action of said pressure fluid in said first and second chambers, or relieving the pressure fluid in said third chamber for releasing said servo piston head for said opening stroke thereof under the action of pressure fluid in said first and second chambers.

10 2. A spray gun according to claim 1 in which said maneuvering valve has a first position adapted to cause said means controlled thereby to supply pressure fluid to all three of said cylinder chambers and a second position adapted to supply pressure to said first cylinder chamber only and to relieve the pressure in said third cylinder chamber.

15 3. A spray gun comprising a housing, nozzle means on said housing, means for supplying coating material under pressure to said nozzle means, a coating material valve for controlling the flow of such material through said nozzle means, a source of pressure fluid, a cylinder in said housing, a tandem piston having a stem portion thereon connected to said coating material valve, said tandem piston having an intermediate and an outer piston head thereon and being movable in said cylinder to perform alternately opening and closing strokes therein under the action of pressure fluid from said source for controlling said coating material valve, a partition in said housing between said piston heads for sealingly but slidably receiving said stem portion therein, said tandem piston dividing said cylinder in a first cylinder chamber between said partition and outer head, a second cylinder chamber outwardly of said outer head, and a third cylinder chamber between said partition and intermediate head, passage means permanently communicating said second and third cylinder chambers, means for keeping said first cylinder chamber pressurized by pressure fluid from said source during the strokes of said tandem piston, a maneuvering valve, and means controlled by said maneuvering valve for either supplying pressure fluid from said source to said second and third chambers for producing one of the strokes of said tandem piston against the action of said pressure fluid in said first chamber, or relieving the pressure fluid in said second and third chambers for releasing the other stroke of said tandem piston under the action of pressure fluid in said first chamber.

20 4. A spray gun according to claim 3 in which said means for keeping said first cylinder chamber pressurized are check valve means on said outer head opening for pressure fluid flow from said second to said first cylinder chamber, said check valve means being provided by a resilient packing cup included in said outer head.

25 5. A spray gun according to claim 3 in which said passage means are provided in said stem portion.

30 6. A spray gun according to claim 3 in which said maneuvering valve has a first position adapted to cause said means controlled thereby to supply pressure fluid to all three of said cylinder chambers and a second position adapted to supply pressure to said first cylinder chamber only and to relieve the pressure in said second and third cylinder chambers.
